TELEPHONE SYSTEM

James B. Newsom, Great Neck, N. Y., assignor to
 Bell Telephone Laboratories, Incorporated, New
 York, N. Y., a corporation of New York

Application December 20, 1932, Serial No. 648,077

8 Claims. (Cl. 179—27)

This invention relates to telephone systems and more particularly to traffic intercepting equipment for use in automatic telephone systems.

The object of the invention is to provide an improved arrangement for extending intercepted calls to a centralized "A" switchboard.

In automatic telephone systems it is usual to connect an intercepting trunk to blank terminals in the selector and connector banks and also to provide an intercepting trunk from a plugging-up line for intercepting calls to a subscriber whose line is temporarily removed from service. When the intercepting operators' positions are located in the same office as that in which the calls are intercepted, the intercepting trunks terminate in answering jacks at the various positions and in response to their seizure light corresponding answering lamps associated therewith. When one centralized intercepting "A" switchboard is provided for several offices each intercepted call is extended over one of a group of trunks to the centralized "A" switchboard, one such arrangement being disclosed in the patent to John Wicks, No. 1,576,384, March 16, 1926.

According to this invention all intercepted calls in an office, irrespective of the point at which they are intercepted, are concentrated for their extension over a common group of interoffice trunks to a centralized intercepting switchboard by providing finder switches individual to the interoffice trunks and having access to all of the intercepting trunks. Since calls may be intercepted at various stages of completion the intercepting trunks are variously arranged to start an idle trunk finder switch in response to their seizure. If a call is intercepted at a connector or toll selector, ground connected to the sleeve conductor of the intercepting trunk operates a start relay to cause a trunk finder to hunt for the seized trunk; if a call is intercepted at a local selector, a line relay bridged across the line conductors of the intercepting trunk operates to start an idle trunk finder; and if a call is intercepted from a plugging-up line, a ring-up relay connected in series with a condenser across the line conductors operates in response to ringing current to effect the starting of an idle trunk finder. Upon extension of a call by a trunk finder, the associated outgoing trunk responds to ringing current or direct current if the call is intercepted at a connector switch or from a plugging-up line and responds to direct current received over one of the conductors of the intercepting trunk if the call is intercepted at a selector switch. Means are provided for responding to signaling

current over either conductor since ringing current or direct current may be received over either conductor if the call is intercepted at a connector or from a plugging-up line and direct current may be received over the ring conductor if the call is intercepted at a local or toll selector. Means are also provided for reversing the line conductors from the trunk finder in case ringing current is received over the tip conductor in order that the tripping resistance may always be connected to the conductor over which the ringing current is received and in order to maintain the same supervisory conditions as exist when signaling current is received over the ring conductor.

The invention will be better understood by considering a telephone system in which its features have been embodied, such a system being shown schematically in the drawings which form a part of this specification. The use of the invention is not limited, however, to the particular system illustrated and other applications of the invention will readily occur to one skilled in the art.

Referring to the drawings:

Fig. 1 represents schematically a toll line L, a toll operator's cord circuit CO1 position equipment OP and an outgoing trunk circuit T for use in extending calls to a distant step-by-step office;

Fig. 2 shows a toll selector TS in the step-by-step office for use in completing calls incoming from a manual toll office;

Fig. 3 shows a toll connector circuit TC for use in completing calls incoming from a toll office;

Fig. 3a shows a trunk circuit IT1 for intercepting connections extended to blank terminals in the banks of toll selectors;

Fig. 3b shows a similar trunk circuit IT2 for intercepting connections extended to blank terminals in the banks of toll connectors;

Fig. 4 shows an automatic subscriber's station A, a line finder LF and a first selector LS;

Fig. 5 shows a connector LC for completing local calls;

Fig. 5a shows a trunk circuit IT3 for intercepting calls extended to blank terminals in the bank of local selectors;

Fig. 6 shows a plugging-up line circuit PL and an intercepting trunk circuit IT5 from the plugging-up line for extending calls to an intercepting operator;

Fig. 6a shows a trunk circuit IT4 for use in intercepting calls extended to blank terminals in the banks of local connectors;

Fig. 7 shows a trunk finder TF having access to the intercepting trunks from toll and local

selectors, from toll and local connectors and from plugging-up lines;

Fig. 8 shows an outgoing trunk circuit OT associated with a trunk finder, such as is shown in Fig. 7, and used in extending intercepted calls to a centralized intercepting operator's position in the same office or in a distant office;

Fig. 9 shows an incoming trunk circuit IT for receiving incoming intercepted calls;

Fig. 10 shows a cord circuit CC2 for use in answering incoming intercepted calls; and

Fig. 11 shows the manner in which Figs. 1 to 10, inclusive, are to be connected to form an operative arrangement.

The toll operator's cord and position circuits of Fig. 1 may be similar to those shown and described in the patent to R. C. Paine, No. 1,836,549, December 15, 1931. The selector and connector switches of Figs. 2, 3, 4 and 5 are of the well known two-motion step-by-step type as is also the trunk finder of Fig. 7. Reference may be had to pages 53 to 65 inclusive, of the second edition of "Automatic Telephony" by Smith and Campbell, published in 1921, for a description in detail of the construction and operation of such switches.

The various intercepting trunks IT1 from the bank of toll selector TS, IT2 from the bank of the toll connector TC, IT3 from the bank of local selector LS, IT4 from the bank of the local connector LC and IT5 from the plugging-up line PL all terminate in the bank of the trunk finder TF and in the banks of similar trunk finders, each of which is associated with a trunk terminating at the centralized intercepting switchboard. The operation of the system to extend intercepted calls to a centralized intercepting operator's position will be described first for calls incoming from a toll operator's position and second for local calls.

Referring to Fig. 1, a call incoming over toll line L may be answered by inserting plug 101 of the cord CC1 into jack 100. The talking key (not shown) is then operated to extend the connection to the operator's position circuit OP. Upon inquiry the operator receives the number of the called subscriber with which the calling subscriber or operator desired connection. If the called subscriber's line terminates in a distant automatic office, the plug 103 to the cord circuit CC1 is inserted in a jack connected to a trunk leading to the desired office, such for instance as the jack 110. The sleeve relay 111 of the outgoing trunk circuit T is thus operated by the energization of its lower winding in series with the supervisory lamp 104 of the cord circuit CC1, the current being insufficient to light the lamp. Upon operation of the dial key (not shown), a circuit is closed from battery (not shown) in the position circuit through the upper conductor of cord CC1 and plug 103, upper spring of jack 110, and through the upper back contact and winding of relay 112, to ground. Relay 112 operates, locks under control of the sleeve relay 111, and closes the dialing circuit from battery at the back contact of the release magnet 240 of the toll selector TS, through the upper winding of line relay 201, upper outer back contact of relay 211, lower back contact of relay 206, left lower winding of repeating coil 250, over the lower conductor of the interoffice trunk line 120, through the lower back contact of relay 117 in the outgoing trunk circuit T, outer lower back contact of relay 113, inner upper front contact of relay 112, tip conductors of jack 110, plug 103 and cord CC1 through the interrupter contacts of the dial 105,

back through the ring conductors of cord CC1, plug 103 and jack 110, lower front contact of relay 112, upper back contact of relay 113, winding of polarized relay 114, upper back contact of relay 117, over the upper conductor of trunk 120, outer upper back contact of relay 206, to ground at the inner upper back contact of relay 206. The line relay 201 of the selector TS operates thereby closing an obvious circuit for energizing release relay 202. Relay 202 connects ground at 10 its upper front contact to conductor 219, causing the operation of relay 210. The circuit for operating relay 210 is traced from battery through the winding of relay 210, inner upper back contact of relay 211, lowermost back contact of relay 208, 15 to the ground on conductor 219.

When the toll operator dials the first digit of the called subscriber's number the line relay 201 responds to the train of impulses thereby created, in the usual and well known manner. The first release of relay 201 closes a circuit from battery through the winding of the vertical stepping magnet 220, winding of relay 203, upper back contact of relay 212, lower front contact of relay 202, to ground at the back contact of relay 201. The vertical stepping magnet 220 and relay 203 both operate, the operation of the magnet being effective to step the brushes 215, 216, 217 and 218 up to the first level of the terminal bank. Relay 203 closes a circuit from battery through the winding of relay 204, inner front contact of relay 203, over conductor 219 to ground at relay 202. Relay 204 operates and it locks through its inner lower front contact and lowermost back contact of relay 212 to the ground on conductor 219. As soon as the shaft and brushes of the switch move out of normal position, the vertical off-normal springs VON are actuated, thereby closing a circuit for operating relay 205; this circuit is traced from battery through the back contact 40 of the release magnet 240, upper contacts of the VON springs, winding of relay 205, outer front contact of relay 203 to the ground on conductor 219. Relay 205 locks to ground at its left front contact, under control of the back contact of the rotary stepping magnet 230, but independent of the continued operation of relay 203. The reoperation of relay 201 at the end of the first impulse causes the release of the magnet 220. Each succeeding release and reoperation of line relay 50 201 in response to the dialing of the first digit of the called subscriber's number causes a corresponding operation and release of the magnet 220, thereby stepping the selector brushes up to the level which corresponds to the digit dialed. 55 Being slow to release, relay 203 remains operated until all of the first train of impulses have been received. Relay 202 is also slow to release and remains operated during the receipt of dial impulses.

When relay 203 releases after all of the first train impulses incoming to relay 201 have been received, a circuit for operating the rotary stepping magnet 230 is traced from battery through the winding of magnet 230, right front contact of relay 205, back contact of relay 203, over conductor 219 to ground at relay 202. The operation of the magnet 230 rotates the brushes 215, 216, 217 and 218 into engagement with the first set of terminals in the selected level and also opens the 70 circuit through the winding of relay 205. Relay 205 releases thereby opening the circuit through the winding of the magnet 230; and magnet 230 releases. The first set of terminals are now tested to determine whether they are idle or busy; the 75

test circuit is traced from battery through the back contact of release magnet 240, upper contact of the VON springs, winding of relay 205, back contact of rotary magnet 230, through the inner 5 lower back contact of relay 212, and through the sleeve or test brush 217 to the test terminal of the engaged set of terminals. If the first set of terminals is idle, the test terminal is not connected to ground and relay 212 is operated in a 10 circuit from battery through the back contact of release magnet 240, upper contact of the VON springs, winding of relay 205, back contact of rotary stepping magnet 230, winding of relay 212, over conductor 219 to ground at relay 202; being 15 marginal, relay 205 does not operate in this circuit. If the first set of terminals is busy, the winding of relay 212 is short circuited by the busy ground potential on the test terminal, which potential is effective to reoperate relay 205. The rotary stepping magnet 230 is thus reoperated to 20 advance the brushes to the next set of terminals. Reoperation of relay 205 and magnet 230 continues as long as the test brush 217 encounters busy potential, but as soon as an idle set of terminals is reached, relay 212 operates as above described. Relay 212, operated, connects the ground on conductor 219, through its inner lower front contact, and through test brush 217 to the test terminal to prevent selection of the trunk connected 25 to these terminals by any other hunting selector having access thereto. The busy ground is also effective as a holding potential connected through brush 217 and terminal 223 to hold the succeeding switches employed in establishing the desired connection.

The levels of the toll selector banks which represent assigned groups of telephone numbers may connect to intermediate toll selectors which in turn have access to groups of toll connectors. In 40 the drawings, however, the terminals 231, 232, 233 and 234 are shown connected directly to the toll connector TC, intermediate selectors being omitted. The terminals 221, 222, 223 and 224 represent a level of the toll selector bank in which 45 the terminals are connected to intercepting trunk circuits, the corresponding digit being one which represents an unassigned group of subscribers' numbers.

Assume, first, that the call from the toll operator's position in Fig. 1 is extended over trunk T and toll selector TS to the toll connector TC, the brushes of selector TS having been advanced into engagement with terminals 231, 232, 233 and 234. With relay 212 operated, a circuit is closed 50 for operating the line relay 301 of connector TC; this circuit is traced from battery through the lower winding of relay 301, lowermost back contact of relay 306, terminal 232 and brush 216 of selector TS, middle lower front contact of relay 212, lower front contact of relay 201, inner lower back contact of relay 208, right lower winding of repeating coil 250, resistance 253, upper front contact of relay 204, upper right winding of repeating coil 250, upper back contact of relay 208, 55 upper front contact of relay 212, brush 215 and terminal 231, uppermost back contact of relay 306, and through the upper winding of relay 301 to ground. Relay 301 closes an obvious circuit for operating the release relay 302. Relay 302 locks 60 through its inner upper front contact, the inner upper back contact of relay 304, conductor 314, inner lower back contact of relay 306, conductor 313, terminal 233 and brush 217, inner lower front contact of relay 212, over conductor 219 to ground 65 at relay 202. This ground is further extended 70 at relay 202.

from conductor 314 through terminal 234 and brush 218, the lowermost front contact of relay 212, and through the lower front contact of relay 204 to hold relay 204 operated.

When the toll operator dials the next digit of the called subscriber's number, relay 201 of selector TS alternately releases and reoperates causing the corresponding release and reoperation of relay 301 of connector TC, once for each dial impulse. The first release of relay 301 closes 10 a circuit from ground at the inner upper back contact of relay 303, back contact of relay 301, inner lower front contact of relay 302, normally closed contacts of the vertical off-normal springs VON, winding of relay 303, and through the winding of the vertical stepping magnet 320 to battery. The magnet 320 operates thereby advancing the brushes 317, 318 and 319 up to the first level of the terminal bank. Relay 303 also operates and as soon as the switch moves out of 20 its normal position the circuit for energizing the windings of magnet 320 and relay 303 is traced through the front contact of relay 303 and the upper front contact of the VON springs instead of through the normally closed contact of the 25 VON springs. The magnet 320 releases when relay 301 reoperates at the end of the first impulse, each additional impulse causing the reoperation and release of magnet 320 to advance the connector switch brushes to the level corresponding 30 to the digit dialed. Relay 303 is slow in releasing and remains operated until all of the impulses of the series have been received. Relay 302 is also slow in releasing and remains operated during receipt of dial impulses.

When the next and last digit of the called number is dialed, the first release of relay 301 closes a circuit from ground at the inner upper back contact of relay 306, back contact of relay 301, inner lower front contact of relay 302, upper 40 front contact of the VON springs, back contact of relay 303, winding of relay 305, and through the winding of the rotary stepping magnet 330 to battery. The operation of magnet 330 advances the brushes 317, 318 and 319 to the first 45 set of terminals in the selected level and the operation of relay 305 connects the winding of test relay 304 to the sleeve brush 319. The magnet 330 releases when relay 301 reoperates at the end of the first impulse, each additional impulse 50 causing the reoperation and release of magnet 330 to advance the brushes into engagement with the set of terminals corresponding to the digit dialed. Relay 305 is slow in releasing and remains operated until all of the impulses of the 55 series have been received. Relay 304, being somewhat slow in operating, does not operate if the brush 319 engages a grounded test terminal during the advance of the brushes; but as soon as the brushes come to rest on the selected set of 60 terminals, relay 304 operates in case the called line is busy as indicated by the presence of a ground potential on the test terminal.

Assuming that the called line is the line 380 connecting station C to terminals 331, 332 and 65 333 of the switch TC and that this line is idle when selected, the release of relay 305 closes a circuit from battery through the winding of the cut-off relay 381 of line 380, through terminal 333 and brush 319, lower back contact of relay 305, inner lower back contact of relay 304, middle upper back contact of relay 306, middle upper front contact of relay 302, through the upper winding of relay 306 to the holding ground from relay 202 of selector TS on sleeve conductor 313. 70 75

Relay 306 is sufficiently energized to close its inner lower front contact and thus lock through its lower winding to the holding ground. The operation of relay 306 extends the connection 5 from the calling line through its outermost front contacts, the outermost front contacts of relay 302, the outermost back contacts of relay 304, and through brushes 317 and 318 to the called line. The operation of relay 306 also disconnects 10 control conductor 314 from sleeve conductor 313 thereby causing the release of relay 204 of the toll selector TS. The release of relay 204 closes a circuit from battery at the back contact of release magnet 249, lower front contacts of the 15 VON springs, winding of relay 206, to ground at the lowermost back contact of relay 204. Relay 206 operates, thereby reversing the current over trunk 120, the tip conductor of trunk 120 being reconnected through the upper left winding of repeating coil 250, the upper front contact of relay 206, resistance 251, uppermost back contact of relay 211, upper winding of relay 201, to battery at the back contact of release magnet 249; and the 20 ring conductor of trunk 120 is connected through the lower left winding of repeating coil 250, inner lower front contact of relay 206, resistance 252, inner lower back contact of relay 211, through the lower winding of relay 201 to ground. This reversal of current is effective to operate the 25 polarized relay 114 of the trunk circuit T and a polarized relay (not shown) in the toll operator's position equipment, thereby causing the dial 105 to be disconnected from the cord CC1. The operation of relay 114 closes an obvious circuit for 30 operating relay 113. Relay 113 locks under control of relay 111 and the connection from the line conductors of cord CC1 is extended through the front contacts of relays 112 and 113 to the left-hand windings of repeating coil 118. The inner 35 end of the lower left-hand winding of coil 113 is further connected through the winding of relay 117 to ground, this relay being under control of the ringing key (not shown) of the cord circuit. With relay 113 operated, the supervisory relay 40 115 and right-hand windings of repeating coil 118 are bridged across the conductors of trunk 120 leading to the toll selector TS in the distant step-by-step office, thereby operating relay 115 of trunk circuit T and maintaining the energization of the line relay 201 of the toll selector TS. The operation of relay 115 connects the upper winding of relay 111 in parallel with the 45 lower winding, thus reducing the resistance of the sleeve circuit of the cord CC1 sufficiently to 50 light the supervisory lamp 104.

The aforementioned operation of relay 306 of the toll connector TC also causes the release of relay 301 but relay 302 is held operated through its upper winding and inner upper front contact, inner upper back contact of relay 304, control conductor 314, terminal 234 and brush 218, the lowermost front contact of relay 212, inner lower back contact of relay 204, outer lower back contact of relay 211, outer front contact of relay 210, outer lower back contact of relay 208, over conductor 219 to ground at release relay 202.

Further operation now awaits the operation of the ringing key at the toll operator's position in response to which relay 117 of trunk circuit T is 55 operated. Relay 117 connects the alternating ringing current source 119 across the outgoing conductors of trunk 120, thereby causing the operation of relay 207 of the toll selector TS. Relay 207 closes a circuit for operating relay 208. The operation of relay 208 disconnects the hold-

ing ground on conductor 219 from brush 218, thereby causing the release of relay 302 of the connector TC. The operation of relay 208 also causes the release of relay 210 and the release of relay 210 reconnects the ground on conductor 219 to the brush 218; relay 210 is slow in releasing to insure the release of relay 302 of the connector. The release of relay 302 closes a ringing circuit from the source of ringing current 325, middle lower front contact of relay 306, lower winding and outer lower back contact of relay 302, outer lower back contact of relay 304, brush 318 and terminal 332, over line 380 and through the ringer (not shown) at station C, back through terminal 331 and brush 317, outer upper back contacts of relays 304 and 302, to ground at the middle upper front contact of relay 306. When the ringing key at the toll operator's position is released relays 207 and 208 release and relay 210 reoperates. When the subscriber at station C removes the receiver to answer the call, relay 302 is operated by the current through its lower winding and this relay is again locked through its upper winding and inner upper front contact over the control conductor 314 25 to ground at relay 202 of the toll selector TS. Talking current is now supplied to the called subscriber in a circuit from battery through the lowermost front contact of relay 206 of the toll selector TS, lower winding of supervisory relay 30 213, middle lower back contact of relay 204, lower right winding of repeating coil 250, inner lower back contact of relay 208, lower front contact of relay 201, middle lower front contact of relay 212, brush 216 and terminal 232, lowermost front contacts of relays 306 and 302 of connector TC, lowermost back contact of relay 304, brush 318 and terminal 332, over line 380 and through the subscriber's telephone at station C, back through terminal 331 and brush 317, the uppermost back 40 contact of relay 304, the uppermost front contacts of relays 302 and 306, through terminal 231 and brush 215, upper front contact of relay 212 of selector TS, upper back contact of relay 208, upper right winding of repeating coil 250, upper 45 back contact of relay 204, and through the upper winding of relay 213 to ground. The supervisory relay 213 operates to effect the operation of relay 211. Relay 211 disconnects the windings of relay 201 from the left windings of repeating coil 250 thereby causing the release of relay 115 of the trunk circuit T. With relay 115 released the circuit through the upper winding of relay 111 is opened thus causing the supervisory lamp 104 to be extinguished. The voice 50 currents are now transmitted through repeating coils 118 and 250, the trunk 120 having no direct current flowing thereover. Relay 201 of the toll selector is held operated by connecting resistance 214 in series with its windings, this connection being made at the next-to-the inner lower front contact of relay 211. The operation of relay 211 also causes the release of relay 210.

When the called subscriber replaces the receiver on the receiver hook, supervisory relay 213 55 releases causing the release of relay 211. Relay 201 now holds in the circuit over trunk 120 causing the reoperation of relay 115 of trunk circuit T and the lighting of supervisory lamp 104. Relay 210 reoperates. The operator may rering the 60 called subscriber if this is found desirable. When the plug 103 is removed from jack 110, relays 111, 112 and 113 release, thus restoring trunk circuit T to normal. The release of relay 113 opens the bridge across trunk 120 causing the 65 70 75 80 85 90 95 100 105 110 115 120 125 130 135 140 145 150 155 160 165 170 175 180 185 190 195 200 205 210 215 220 225 230 - release of relay 201 of the selector TS followed by the release of relay 202. The release of relay 202 causes the release of relays 210 and 212 of selector TS and the release of relays 302 and 306 of the connector TC. The release of relay 202 closes a circuit from battery through the middle front contact of the VON springs, winding of release magnet 240, through back contacts of relays 202 and 201 to ground. Magnet 240 operates causing the shaft and brushes of switch TS to be restored to normal in the usual manner and causing the release of relay 206. When the shaft reaches normal the VON springs are restored to normal, releasing magnet 240.
- 15 The release of relays 302 and 306 of connector TC closes a circuit from battery through the winding of release magnet 340, lower front contact of the VON springs, inner lower back contact of relay 302, back contact of relay 301, to ground at the inner upper back contact of relay 306. Magnet 340 operates causing the shaft and brushes of switch TC to be restored to normal. When the shaft reaches normal the VON springs are restored to normal releasing magnet 340.
- 20 Should the called line 380 be busy when seized by the switch TC as hereinbefore described, the operation of test relay 394 disconnects the tip and ring conductors of the connector from the brushes 317 and 318 to prevent interference with the call already in progress over the called line. When relay 305 releases, a locking circuit for relay 304 is closed before the operating circuit is opened, the locking circuit being traced from battery through the winding of relay 304, back contact of the continuity springs of relay 305, inner lower front contact of relay 304, middle upper back contact of relay 306, middle upper front contact of relay 302, upper winding of relay 306, to the holding ground from selector TS on conductor 313. Relay 306 is sufficiently energized to close its inner lower front contact thus locking through its lower winding to the ground on conductor 313. The operation of relay 306 connects ground through its inner upper front contact to the inner lower armature of relay 304 to hold relay 304. With relay 304 operated, relay 302 holds through its inner upper front contact and the inner upper front contact of relay 304 to the holding ground on conductor 313. The operation of relay 306 also causes the release of relay 301 and disconnects the holding ground on conductor 313 from the control conductor 314 thereby causing the release of relay 204 of the toll selector TS. The release of relay 204 causes the operation of relay 206, reversing the current over trunk 120. This reversal of current operates relay 114 of trunk circuit T and causes the dial 105 to be disconnected. Relay 113 operates to connect the left-hand windings of repeating coil 118 to the cord CC1 and to bridge the winding of relay 115 across the conductors of trunk 120 as hereinbefore described. With relay 204 of the toll selector TS released a circuit is closed from ground through interrupter 315 of the toll connector TC, through the lowermost front contacts of relays 304, 302 and 306, terminal 232 and brush 216 of the toll selector TS, middle lower front contact of relay 212, lower front contact of relay 201, middle lower back contact of relay 208, right lower winding of repeating coil 250, middle lower back contact of relay 204, lower winding of relay 213, and through the lowermost front contact of relay 206 to battery. The alternate closing and opening of this circuit under control of interrupter 315 causes the alternate operation and release of relays 213 and 211. Relay 211 thus alternately opens and closes the connection from battery and ground through the windings of relay 201 to the conductors of trunk 120 to cause the alternate release and reoperation of relay 115 of trunk circuit and the flashing of lamp 104 to indicate that the called line is busy. When the toll operator removes plug 103 from jack 110, the trunk circuit T, toll selector TS and connector TC are restored to normal in the same manner as hereinbefore described, the release of relay 306 of the connector TC causing the release of relay 304.
- 15 Assume, next that the call from the toll operator's position in Fig. 1 is extended over trunk T and though toll selector TS to the intercepting trunk circuit IT1 in Fig. 3a, the brushes of switch TS having been advanced into engagement with terminals 221, 222, 223 and 224. Since relay 204 requires a locking circuit through its lower front contact and brush 218 in order to remain operated after relay 212 operates and since the trunk IT1 has no conductor connected to terminal 224 with which brush 218 is in contact, the aforementioned operation of relay 212 causes the release 20 of relay 204. With relay 204 released, relay 206 operates as hereinbefore described thereby connecting battery through the lowermost front contact of relay 206, lower winding of relay 213, middle lower back contact of relay 204, lower right winding of the repeating coil 250, inner lower back contact of relay 208, lower front contact of relay 201, middle lower front contact of relay 212, brush 216 and terminal 222 to the ring conductor 352 of trunk IT1 and connecting ground through the upper winding of relay 213, upper back contact of relay 204, upper right winding of repeating coil 250, upper back contact of relay 208, upper front contact of relay 212, brush 215 and terminal 221 to the tip conductor 351 of trunk IT1. The operation of relay 206 is also effective to reverse the current over trunk 120 and thus cause the disconnection of dial 105, the extension of the line conductors of cord CC1 to the windings of repeating coil 118, the lighting of supervisory lamp 104, and the connection of the winding of relay 115 across the conductors of trunk 120, all as hereinbefore described. Further operation of the dial is ineffective and the lighting of lamp 104 prior to the completion of dialing indicates 30 that the call is being intercepted and the ringing key will not be operated.
- 40 Upon seizure of the trunk circuit IT1, a circuit is closed from the busy and holding ground connected to the test terminal 223, over test conductor 350, through the lower back contact of relay 355 of trunk circuit IT1 and through the winding of trunk relay 354 to battery. Relay 354 operates thereby connecting the winding of cut-off relay 355 over the sleeve conductor 353 of trunk IT1 to test terminals in the banks of the trunk finders which have access to this trunk. Thus, the line conductors 351 and 352 of trunk IT1 are connected to terminals 711 and 712 in one of the terminal banks of finder TF and the sleeve conductor 353 is connected to the corresponding test terminal 713 in the test bank of finder TF. Relay 354 also closes a circuit from ground through the upper back contact of relay 355, the upper front contact of relay 354, over 45 the group conductor 700, through the winding of group relay 701 to battery. Group relay 701 operates thereby connecting ground through its right front contact, over conductor 702, to the corresponding segment of the vertical commu- 50

- 75

tators of all of the trunk finders having access to the group of trunks which includes the trunk IT1. In the drawings this is shown as the second segment of commutator 703 corresponding to the second level of the bank of switch TF.

Assuming the trunk finder TF to be the first idle trunk finder in the group, the operation of relay 701 also closes a circuit for operating relay 705; this circuit is from ground at the left front contact of relay 701, over the start conductor 704, through the inner upper back contact of relay 708 and winding of relay 705 to battery. Relay 705 connects ground through its inner lower front contact over conductor 773 to the sleeve conductor of the outgoing trunk circuit OT in Fig. 8 and closes a circuit, for operating relay 707, from battery through the uppermost back contact of relay 708, upper winding of relay 707, back contacts of the rotary stepping magnet 730 and vertical stepping magnet 720, to ground at the lowermost front contact of relay 705. Relay 707 operates thereby closing a circuit from battery at the uppermost back contact of relay 708, winding of the vertical stepping magnet 720, lowermost back contact of relay 709, front contact of relay 707 to ground at the lowermost front contact of relay 705. The magnet 720 operates, thereby stepping the two sets of brushes 761, 762 and 763 and 764, 765 and 766 up to the first level of terminals in the associated banks. The vertical commutator brush 717 is also stepped up to make contact with the first segment of the commutator 703. The operation of magnet 720 also causes the release of relay 707; and the release of relay 707 causes the release of magnet 720.

Although the calling trunk may be connected to terminals in the banks associated with brushes 761, 762 and 763 or to terminals in the banks associated with brushes 764, 765 and 766, the intercepting trunks IT1, IT2, IT3, IT4 and IT5 are all shown connected to terminals in the second level of the banks with which the brushes 761, 762 and 763 are associated and description 40 of the terminal hunting operating of the trunk finder will, therefore, be limited to the case where the calling trunk is encountered by the latter set of brushes. Since the trunk, for which the trunk finder TF is seeking, is connected to 45 terminals in the second level, the commutator brush 717 does not encounter ground potential on the first commutator segment to stop further hunting. With magnet 720 released, relay 708 reoperates again closing the circuit for operating 50 magnet 720. The brushes are thus stepped up to the second level of the terminal banks. Since trunk IT1 is connected to terminals in the second level, a circuit is closed for energizing relay 709 as soon as the commutator brush 717 comes in 55 contact with the second commutator segment; this circuit is traced from battery through the uppermost back contact of relay 708, upper winding of relay 707, back contact of magnet 730, upper winding of relay 709, commutator brush 60 717, second commutator segment, conductor 702 to ground at the right front contact of group relay 701. This circuit is also effective to hold 65 relay 707 operated. Relay 709 is slow in operating to ensure proper positioning of the brushes before the first rotary step. Relay 709 opens the 70 circuit through the winding of magnet 720 so that magnet 720 releases. Relay 709 also closes a circuit, for operating the rotary stepping magnet 730, from battery through the winding of magnet 730, lowermost front contact of relay

709, front contact of relay 707 to ground at the lowermost front contact of relay 705. The operation of magnet 730 steps the two sets of brushes into contact with the first set of terminals in the second level of each of the associated banks. The circuit through the upper windings of relays 707 and 709 is opened when magnet 730 operates and is also opened at the commutator due to brush 717 being rotated out of alignment with the segments. Relay 707 releases but relay 709

is held operated in a circuit from battery through the uppermost back contact of relay 708, winding of magnet 720, lower winding and inner lower front contact of relay 709, to ground at the lowermost front contact of relay 705; the current in this circuit is not sufficient to operate the magnet 720. If the first set of terminals in the second level is not the set to which the calling trunk IT1 is connected, magnet 730 releases when relay 707 releases; relay 707 reoperates when magnet 730 releases and causes the reoperation of magnet 730 to advance the brushes into engagement with the second set of terminals. The alternate reoperation and release of relay 707 and rotary stepping magnet 730 continues until the

test brush 763 encounters test terminal 713 to which conductor 353 is connected; at which time a circuit is closed from battery through the winding of the cut-off relay 355 of trunk circuit IT1, lower front contact of relay 354, conductor 353, terminal 713, brush 763, lower winding of relay 710, lowermost back contact of relay 707 to ground at the inner lower front contact of relay 705. Relay 707 is held

energized, and relay 710 is operated in this circuit sufficiently to close its inner upper front contact. Relay 710 is thus fully energized and locked operated in the circuit from battery through its upper winding and inner upper front contact, conductor 774, front contact of magnet 730, front contact of relay 707, to ground at the lowermost front contact of relay 705. Magnet 730 is held operated under control of relays 709 and 707. The cut-off relay 355 of trunk circuit

IT1 is also operated by closure of the above circuit through brush 763 and terminal 713, thereby disconnecting the ground at the upper back contact of relay 355 from group conductor 730. The operation of relay 355 also causes the release of relay 354, thereby extending the holding ground

at the upper front contact of relay 202 of toll selector TS, over conductors 219 and 350, through the inner front contact of relay 355 and inner back contact of relay 354, to hold relay 355; and from conductor 356 through the outer front contact of relay 355 and the lowermost back contact of relay 354 to sleeve conductor 353 to hold the trunk finder TF in its operated position. The aforementioned operation of relay 710 extends the connection from the toll operator's position, over conductors 351 and 352 of trunk IT1 through terminals 711 and 712 and brushes 761 and 762, outer back contacts of relay 706, outer front contacts of relay 710, over conductors 771 and 772 of the trunk finder TF to the outgoing trunk circuit OT. Relay 710 also closes a circuit from battery through the lower winding of relay 708, middle upper front contact of relay 710, over conductor 770 to ground at the lower front contact of the vertical off-normal springs VON; the VON springs were operated when the shaft and brushes stepped up to the first level. The operation of relay 708 causes the release of relay 705 and extends the holding ground on sleeve conductor 353 (from the toll selector TS) through terminal

713 and brush 763, through the inner lower front contact of relay 710, the inner lower back contact of relay 706, and the lowermost front contact of relay 708 to the sleeve conductor 773 leading 5 to the outgoing trunk circuit OT. This holding ground is further extended from conductor 773, through the inner lower front contact of relay 708, over conductor 774, to hold relay 708 operated. Relay 708 also disconnects the battery at 10 its uppermost back contact from the windings of relay 707 and magnet 720 and short circuits the lower winding of relay 707 thereby causing the release of relays 707 and 709. The group relay 701 releases when relay 355 of the trunk circuit 15 IT1 releases unless another trunk in the same group is awaiting connection to another outgoing trunk, in which case the ground at the left front contact of relay 701 is extended over conductor 704, through the outer upper front contact of relay 708, over conductor 769 to the next 20 trunk finder (not shown) in the group. The rotary magnet 730 releases when relay 709 releases leaving only relays 708 and 710 operated during the further extension of the connection to 25 the intercepting operator.

With conductors 351 and 352 of intercepting trunk IT1 extended over conductors 771 and 772 to the outgoing trunk circuit OT, and with relays 204 and 203 of the toll selector TS normal, 30 relay 302 of the outgoing trunk circuit OT is operated in a circuit from ground at the lower back contact of relay 810, resistance 806, lower winding of relay 802, ring conductor 772 of trunk finder TF, lowermost front contact of relay 710, lowermost back contact of relay 706, brush 762 and 35 terminal 712 of trunk finder TF, conductor 352 of intercepting trunk IT1, terminal 222 and brush 216 of toll selector TS, middle lower front contact of relay 212, lower front contact of relay 201, inner lower back contact of relay 208, right lower winding of repeating coil 250, middle lower back contact of relay 204, lower winding of relay 213, lowermost front contact of relay 206, to battery. The resistance 806 is high enough to prevent the 40 operation of relay 213 in this circuit. Relay 802 closes a locking circuit from battery through its upper winding, outer lower back contact of relay 826, upper back contact of relay 810, to ground at the inner front contact of relay 802. The operation 45 of relay 802 connects ground through its outer front contact to sleeve conductor 819 and closes an obvious circuit for operating relay 807. Relay 807 closes a circuit for operating relay 808, relay 808 closes a circuit for operating relay 50 809, and relay 809 closes a circuit for operating relay 810. Ground at the front contact of relay 809 is connected through the lowermost front contact of relay 810 to the sleeve conductor 819. With relay 810 operated, the direct current circuit through the lower winding of relay 802 and resistance 806 is opened, the lower winding of relay 802 and condenser 804 in series being bridged across conductors 771 and 772; and conductor 772 is further extended through the lower back contact of relay 825, the middle lower front contact of relay 810, the lower front contact of relay 808, and through resistance 820 to ground. The resistance 820 is low enough to cause the operation of the tripping relay of a toll or local connector in the usual manner on calls intercepted at the banks of such switches. The release of relay 802 causes the release of relay 807 and the release of relay 807 causes the release of relay 808. Relay 808 is slow in releasing to 55 insure the low resistance 820 being connected to conductor 772 long enough to operate the tripping relay on calls which are being received from a connector. Before resistance 820 is disconnected, a circuit is closed through both windings of the supervisory relay 213 of the toll selector TS and through the supervisory relay 812 of the outgoing trunk circuit OT. This circuit is traced from battery through the lowermost front contact of relay 208, lower winding of relay 213, middle lower back contact of relay 204, right lower winding of repeating coil 250, inner lower back contact of relay 208, lower front contact of relay 201, middle lower front contact of relay 212, brush 216 and terminal 222, conductor 352 of trunk IT1, terminal 712 and brush 762 of trunk 10 15 finder TF, lowermost back contact of relay 706, lowermost front contact of relay 710, conductor 772, lower back contact of relay 825, middle lower front contact of relay 810, back contact of the continuity springs of relay 808, induction coil 816, 20 winding of polarized relay 811, windings of supervisory relay 812, upper back contact of relay 825, conductor 771, uppermost front contact of relay 710, uppermost back contact of relay 706, brush 761 and terminal 711 of finder TF, conductor 351 25 of trunk IT1, terminal 221 and brush 215 of selector TS, upper front contact of relay 212, upper back contact of relay 208, right upper winding of repeating coil 250, upper back contact of relay 204, upper winding of relay 213 to ground. The 30 resistance of the lower winding of relay 812 of trunk circuit OT is high enough to prevent the operation of relay 213 of selector TS. Relay 812 operates and the polarized relay 811 also operates on an intercepted toll call, the current being in 35 the operating direction. Relay 811 closes a circuit for operating relay 814. Relay 812 closes a holding circuit for relay 809 and closes a circuit for operating relay 813. Relay 813 connects battery and ground through the windings of relay 815, 40 front contacts of relay 813, back contacts of relay 814, to the conductors of trunk 900 thereby operating relay 901 of the incoming trunk circuit IT in the office at which the intercepting operator's positions are located, the winding of 45 relay 901 in series with resistance 902 being connected by the upper back contact of relay 906 across the conductors of trunk 900. Relay 815 is marginal and does not operate until the call is answered by an intercepting operator. Relay 901 50 closes a circuit for lighting lamp 902 associated with the answering jack 903 and closes a circuit through the upper winding of relay 904. Relay 904 operates causing the operation of relay 905. Relay 905 connects the upper conductor of trunk 55 900 through its front contact and through condenser 908 to the source of ringing current 907, thereby transmitting an audible ringing signal over the trunk and through condenser 821 to conductor 817 of the outgoing trunk circuit OT and 60 thence back to the calling subscriber or operator.

When an intercepting operator inserts the plug of an answering cord in jack 903 to answer the call, and assuming the cord CC2 to be the one used, a circuit is closed from battery through the 65 upper back contact of relay 959, winding of relay 952, lower back contact of relay 955, ring conductor of plug 951 and jack 903, to ground at the back contact of relay 906. Relay 952 operates, closing a circuit for operating relay 953 from 70 battery through the lower back contact of relay 959, winding and continuity back contact of relay 953, to ground at the front contact of relay 952. Relay 953 operates thereby closing a locking circuit through its continuity front contact, 75.

through the sleeve conductors of plug 951 and jack 903, and through the winding of relay 906 to ground. Relay 906 operates in this circuit thereby causing the release of relay 901 by opening the bridge across the conductors of trunk 900. With relay 906 operated, the ring conductor of jack 903 is disconnected from ground and connected through the front contact of relay 906 and lower front contact of relay 904 to the lower winding of relay 904. The release of relay 901 extinguishes the lamp 992 and deenergizes the upper winding of relay 904. Relay 904 remains operated temporarily, its lower winding being energized in a circuit traced through the lower front contacts of relays 904 and 906, over the ring conductor of jack 903 and plug 951, lower back contact of relay 955, resistance 965, inner lower front contact of relay 953, to ground at the upper back contact of relay 955. With relay 953 operated, relays 954 and 955 are operated successively, the operation of relay 955 being effective to cause the release of relays 904 and 952. Relay 904 is held operated until the ground is disconnected from the ring conductor of the cord to prevent false operation of relay 815 due to a difference in ground potential between offices. The release of relay 904 causes the release of relay 905, and with relay 955 operated, a circuit is now traced from battery through the upper winding of relay 815 of the outgoing trunk circuit OT, upper front contact of relay 813, lower front contact of relay 814, lower conductor of trunk 900, back contact of relay 904 of the incoming trunk circuit IT, front contact of relay 906, ring conductors of jack 903 and plug 951, lower front contact of relay 955, lower back contact of flashing key 961, windings of relays 956 and 957, induction coil 962, over the tip conductors of plug 951 and jack 903, upper back contact of relay 905, upper conductor of trunk 900, upper front contact of relay 814, lower front contact of relay 813, through the lower winding of relay 815 to ground. Relays 957 and 958 are both operated in this circuit, the current being in the operating direction for polarized relay 958 due to the operation of relay 814 on an intercepted toll call. Relay 958 closes a circuit for operating relay 956 which locks under control of relay 953. The operation of relay 956 prevents the operation of relay 959 and short circuits the windings of relays 957 and 958 causing the release of these two relays and causing the operation of the marginal relay 815 in the outgoing trunk circuit OT. The operation of relay 815 short-circuits the high resistance lower winding of relay 812 thereby causing the operation of the marginal supervisory relay 213 of the toll selector TS. When relay 213 operates, it closes a circuit for operating relay 211, thereby disconnecting the winding of relay 201 from the conductors of trunk 120, but holding relay 201 operated by bridging resistance 214 across its windings. With battery and ground disconnected from trunk 120, relay 115 of the trunk circuit T releases, thereby causing the supervisory lamp 104 of cord circuit CC1 to be extinguished.

Upon operation of the talking key 960, conversation may be carried on between the toll operator and the intercepting operator. The connection is held until released by both the toll and intercepting operator, a holding ground being supplied to the sleeve conductors (219, 353, 773 and 819) from the upper front contact of release relay 202 of the toll selector TS and also from the front contact of relay 809. Should it

be necessary for the intercepting operator to attract the toll operator's attention, the flashing key of cord circuit CC2 is alternately operated and released, thereby intermittently opening the bridge across the cord. The resulting alternate release and reoperation of relay 815 causes the short circuit around the lower winding of relay 812 to be intermittently opened, thereby causing the alternate release and reoperation of relay 213 of the toll selector TS. Relay 211 is thus alternately released and reoperated to cause the alternate operation and release of relay 115 in the trunk circuit T which results in the flashing of the supervisory lamp 104 of the cord circuit CC1.

Upon removal of the plug 103 from jack 110, relay 111 releases thereby causing the release of relays 112 and 113. The release of relay 113 opens the bridge across the conductors of trunk 120 but further release of the connection is under control of the intercepting operator. No disconnect signal is given to the intercepting operator and the plug 951 should be removed from the answering jack as soon as it is no longer necessary to hold the connection. When the plug 951 of cord CC2 is removed from jack 903, relay 953 of the cord circuit and relay 906 of trunk circuit IT release. The release of relay 953 causes the release of relay 956 and the successive release of relays 954 and 955 thus restoring cord circuit CC2 to normal. Relay 906 reconnects the winding of relay 901 in series with resistance 902 across the conductors of trunk 900 thereby causing the release of marginal relay 815 of the outgoing trunk circuit OT. The release of relay 815 opens the short circuit around the high resistance winding of relay 812 to cause the release of the supervisory relay 213 of the toll selector TS. The release of relay 213 is followed by the successive release of relays 211, 201 and 202. With relays 201 and 202 normal, the release magnet 240 of selector TS operates and the selector is restored to normal in the usual manner. Upon disengagement of the brushes of selector TS and terminals 221, 222, 223 and 224, relay 212 of the toll selector releases as do also relays 811 and 812 of the outgoing trunk circuit OT. The release of relay 811 causes the release of relay 814 and the release of relay 812 causes the release of relays 813 and 809. The release of relay 809 causes the release of relay 810 and disconnects the holding ground from sleeve conductor 819 to cause the release of relay 355 of the intercepting trunk circuit IT1 and the release of relay 710 of the trunk finder TF.

When relay 710 of the trunk finder TF releases, a circuit is closed from battery through the winding of release magnet 740, upper front contact of the VON springs, inner upper back contact of relay 709, upper back contact of relay 710, back contact of relay 705, to ground at the lower front contact of the VON springs. The release magnet 740 is thus operated to return the trunk finder to normal. When the shaft of the switch reaches normal, the circuits through the winding of the release magnet 740 and the lower winding of relay 708 are opened. If the start conductor 704 is free from ground potential, when the circuit through the lower winding of relay 708 is opened, or as soon thereafter as conductor 704 is free from ground potential, relay 708 releases. All of the various circuit units involved in extending a call intercepted at the bank of a toll selector to an operator at a central

intercepting switchboard have now been restored to normal.

Should the called line number be an unassigned number in a partially assigned group of one hundred line numbers, the connection is completed by the operation of the toll selector TS and toll connector TC, the terminals corresponding to the unassigned numbers being connected to one or more intercepting trunks. Such a 10 trunk is shown connected to terminals 321, 322 and 323 in the bank of switch TC, the associated trunk circuit IT2 shown in Fig. 3b being similar to the trunk circuit IT1 of Fig. 3a. The trunk IT2 connects to terminals 721, 722 and 723 of 15 trunk finder TF and the further extension of the connection to an intercepting operator's position is completed in a similar manner to that hereinbefore described for the call intercepted by trunk IT1 except that relay 802 responds to 20 either alternating current from the source of ringing current 325 of connector TC or to direct current during the silent interval of the ringing cycle. The direct current path through the 25 lower winding of relay 802 is traced above and the alternating current path is traced through the lower winding of relay 802 and condenser 804 to ground at the lower back contact of relay 810. When resistance 820 is temporarily connected to conductor 772 as hereinbefore described, 30 the tripping relay 302 of connector TC operates to complete the supervisory circuit between the toll selector TS and the outgoing trunk OT. The supervisory operations are similar to those on a call intercepted over trunk IT1, the connector 35 TC being released when the toll selector TS releases in the usual and well known manner.

Consider next a call originated by the subscriber at station A in Fig. 4. The telephone set at station A may be of any type suitable for use 40 in an automatic telephone system, the dial 400 being provided for dialing the number of any subscriber's line with which connection is desired. The line 401 connects station A to the usual line circuit (not shown) in the central 45 office and also to terminals in the banks of a group of line finders one of which designated LF is represented by the brushes 402 and the associated terminals. This line finder may also be of the well known Strowger type. For a 50 disclosure of such a finder and a description of its operation, reference may be had to the patent to H. Hovland No. 1,711,682 granted May 7, 1929.

Assume the line 401 to have been extended through the brushes 402 of line finder LF to the 55 line relay 403 of the associated first selector LS. Relay 403 operates closing an obvious circuit for operating the release relay 404. Relay 404 connects ground through its lower front contact to sleeve conductor 413 to hold the line finder LF in its operated position and to hold the cut-off 60 relay (not shown) of the line 401 in the well known manner. The dialing of the first digit by the subscriber at station causes the alternate release and reoperation of relay 403 in response 65 to the dial impulses thus created. The first release of relay 403 closes a circuit from ground through the uppermost back contact of relay 406, back contact of relay 403, the upper front contact of relay 404, winding of relay 405, and 70 through the winding of the vertical stepping magnet 420 to battery. The relay 405 and magnet 420 operate, the operation of the magnet causing the shaft and brushes of switch LS to be stepped up to the first level of the terminal bank. The 75 reoperation of relay 403 at the end of the first

impulse causes the release of magnet 420. Relay 405 is slow in releasing and remains operated until all of the impulses in the train have been received. Relay 404 is also slow in releasing and remains operated during the receipt of dial impulses. Each succeeding release and reoperation of relay 403 in response to dial impulses are effective to cause a corresponding operation of magnet 420, the brushes 417, 418 and 419 being thereby stepped up to the level of terminals corresponding to the digit dialed. 10

When the shaft of switch LS is moved out of its normal position upon receipt of the first dial impulse, the vertical off-normal springs VON are actuated and with relay 404 operated as above 15 described, a circuit is closed from battery through the winding of relay 407, upper contact of the VON springs, front contact of relay 405, to the holding ground on conductor 413. Relay 407 closes a locking circuit traced from the upper 20 contact of the VON springs, through the bank contact of the rotary stepping magnet 430, conductor 409, and the outer front contact of relay 407 to ground at the uppermost back contact of relay 406. When relay 405 releases after all of 25 the impulses corresponding to the first digit have been received, a circuit is closed from battery through the winding of magnet 430, inner front contact of relay 407, back contact of relay 405, to ground on sleeve conductor 413. The operation of magnet 430 advances the brushes of switch LS into contact with the first set of terminals in the selected level and opens the circuit through the winding of relay 407. The release of relay 30 35 407 causes the release of magnet 430. The release of magnet 430 connects the winding of relay 407, through the upper contact of the VON springs, back contact of magnet 430, to conductor 409 thence through the lowermost back contact of relay 406 to sleeve brush 419 and also 40 from conductor 409 through the winding of relay 406 and the lower back contact of the 11th rotary step springs to the holding ground on conductor 413. If the first set of contacts is idle, relay 406 operates in series with relay 407. Relay 407 is marginal and does not operate unless the first set of terminals is busy, in which case the brush 419 encounters ground potential on the terminal with which it is in contact, the winding of relay 406 being short circuited. With relay 50 407 reoperated, the rotary stepping magnet 430 reoperates thereby advancing the brushes of switch LS to the next set of terminals in the selected level. Relay 407 and magnet 430 thus continue 55 their cycle of operations as above described to advance the brushes of switch LS until an idle set of terminals is encountered at which time relay 406 operates to extend the connection from line 401 through its inner front contacts to brushes 417 and 418. With relay 406 operated 60 the sleeve conductor 413 is connected through the lowermost front contact of relay 406 to sleeve brush 419. The operation of relay 406 also causes the release of relays 403 and 404. Relay 404 being slow in releasing maintains the holding ground 65 on conductor 413 until a holding ground has been supplied through brush 419 from the succeeding switch or trunk as a result of its seizure as hereinafter described. Relay 406 is thus held operated, after relay 404 releases, by the holding 70 ground supplied through brush 419.

The levels of the local selector banks which represent assigned groups of telephone numbers may connect to intermediate selectors which in turn have access to groups of local connectors. 75

In Fig. 4, however, the terminals 431, 432 and 433 are shown connected directly to the local connector LC of Fig. 5. The terminals 421, 422 and 423 represent a level of the first selector bank 5 in which the terminals are connected to intercepting trunk circuits, the corresponding digit being one which represents an unassigned group of subscribers' numbers.

Assuming first that the call is for an assigned 10 number and that brushes 417, 418 and 419 have been advanced into engagement with terminals 431, 432 and 433, the connection from line 401 is extended through brushes 417 and 418 and terminals 431 and 432, and through the inner 15 back contacts of relay 504 of connector LC to the windings of line relay 501. Relay 501 operates, in turn causing the operation of relay 502. Relay 502 connects ground through its lower front contact over sleeve conductor 513 to test terminal 20 433 to hold relay 406 of the selector S1 and also to hold the line finder LF in its operated position and to hold the cut-off relay (not shown) of the line 401 all in the well known manner. When the calling subscriber dials the penultimate digit 25 of the called subscriber's number, relay 501 is alternately released and reoperated in response to the dial impulses thus created. The first release of relay 501 closes a circuit from ground at its back contact, through the inner upper front contact 30 of relay 502, normally closed contact of the vertical off-normal springs VON, winding of relay 503 and through the winding of the vertical stepping magnet 520 to battery. The relay 503 and magnet 520 both operate, the operation of 35 the magnet stepping the shaft and brushes of switch LC up to the first level of the terminal bank. When relay 501 reoperates, magnet 520 releases, but relay 503 is slow in releasing and remains operated until all of the impulses in the 40 train have been received. Relay 502 is also slow in releasing and remains operated until the connection is released by the calling subscriber. Each succeeding release of relay 501 causes the 45 reoperation of magnet 520 thereby advancing the brushes 517, 518 and 519 up to the level corresponding to the digit dialed. After the switch is advanced from its normal position in response to the first impulse the circuit for holding relay 503 and reoperating magnet 520 is traced through 50 the upper front contact of the vertical off-normal springs VON and the front contact of relay 503 instead of through the normally closed contact of the VON springs.

When relay 501 releases in response to the first 55 impulse created by the dialing of the last digit of the called subscriber's number, relay 505 and the rotary stepping magnet 530 are operated in a circuit from battery through the winding of magnet 530 and outer upper back contact of relay 60 511 in parallel with battery through the winding of relay 505, through the upper back contact of relay 507, back contact of relay 503, upper front contact of the VON springs, inner upper front contact of relay 502, to ground at the back contact of relay 501. The operation of relay 505 65 renders the energization of this relay and magnet 530 independent of relay 507, the upper front contact of relay 505 being in parallel with the upper back contact of relay 507. The operation of magnet 530 advances the brushes 517, 518 and 519 into contact with the first set of terminals in the selected level. The reoperation of relay 70 501 at the end of the first impulse causes the release of magnet 530. Each succeeding release 75 of relay 501 causes the reoperation of magnet

530, thereby advancing the brushes of switch LC into engagement with the set of terminals connected to the line of the called subscriber. Relay 505 is slow in releasing and remains operated until all of the impulses have been received. Before relay 505 releases, a busy test circuit is traced from battery through the winding of relay 507, inner upper back contact of relay 511, lower front contact of relay 505, through sleeve brush 519 to the sleeve terminal of the selected line. 10 If the line is busy relay 507 operates due to there being a busy-ground potential on this terminal. If relay 507 operates, it remains operated after relay 505 releases the holding circuit being traced through the inner back contact of relay 505 and the outer front contact of relay 507 over conductor 513 to ground at the lower front contact of relay 502. A busy tone is transmitted to the calling station by connecting the left-hand winding 15 of the tone source 512 through the inner front contact of relay 507 to the lower one of talking condensers 500.

Assuming that the called line is the line 580 connecting the station B to the terminals 541, 542 and 543 and that this line is idle, the release of relay 505 closes a circuit from battery through the winding of the cut-off relay (not shown) of line 580, through terminal 543 and brush 519, outer back contact of relay 505, lower winding of relay 511, lower back contact of relay 507 to ground at relay 502. Relay 511 is sufficiently energized by the current through its lower winding to close its inner upper front contact. The circuit from battery through its upper winding and inner upper front contact over conductor 514 to ground at the uppermost front contact of relay 502 is effective to complete the operation of relay 511. With relay 511 operated, ground is connected through its next to the outer lower front contact to sleeve brush 519 as a line busy condition. With relay 511 operated, a signaling circuit is closed from the ringing current source 525, through the inner lower front contact of relay 511, lower winding and lower back contact of relay 506, lowermost front contact of relay 511, brush 518, terminal 542, over the line 580 and through the ringer (not shown) at station B, back through terminal 541 and brush 517, uppermost front contact of relay 511, to ground at the upper back contact of relay 506. When the subscriber at station B removes the receiver, relay 506 is energized sufficiently by the current through its lower winding to operate its inner upper front contact thereby closing a circuit from battery through its upper winding and inner upper front contact to ground on conductor 514. The operation of relay 506 connects a source of talking current to the line 580; battery is connected through the upper winding of relay 504 and uppermost front contacts of relays 506 and 511 to brush 517 and ground is connected through the lower winding of relay 504 and lowermost front contacts of relays 506 and 511 to brush 518. With the receiver removed from the receiver hook at station B relay 504 is operated thereby reversing the connections between the windings of relay 501 and the line conductors incoming to the connector LC. The current is thus reversed over the calling line circuit to indicate that the 70 called subscriber has answered the call. Talking current is furnished to the calling station through the windings of relay 501, the voice frequency currents being transmitted through condensers 500.

When the connection is released by the subscriber at station A, relay 501 releases and when the receiver is replaced at station B relay 504 releases. The release of relay 501 causes the release of relay 502. Relays 506 and 511 are held until relay 502 and 504 are both released. With relays 501, 502 and 511 normal, a circuit is closed from battery through the winding of release magnet 540, lower contact of the VON springs, lower back contact of relay 511, and upper back contacts of relays 502 and 501 to ground. The operation of magnet 540 causes the switch to restore to normal in the usual manner. When the shaft and brushes reach normal position, the circuit through the winding of magnet 540 is opened at the VON springs.

Upon release of relay 502, as above described, the holding ground is disconnected from conductor 513 thereby causing the release of relay 406 of the selector LS and the release of the line finder LF and the release of the cut-off relay (not shown) of line 401, the line finder LF being restored to normal in the usual manner. The release of relay 406 closes a circuit from battery through the winding of release magnet 440, lower contact of the VON springs and upper back contacts of relays 404, 402 and 406 to ground. The operation of magnet 440 causes the switch LS to restore to normal in the usual manner. When the shaft and brushes reach normal position, the circuit through the winding of magnet 440 is opened at the VON springs.

If the selector LS is advanced to a level of the terminal bank which represents an unassigned group of subscribers' numbers, the call is extended to an intercepting operator, the terminals in this level being connected to one or more intercepting trunks. Thus, the terminals 421, 422 and 423 in the bank of selector LS are shown connected to the intercepting trunk IT3 in Fig. 5a. Since the local selectors have no means for signaling over a selected trunk, as do the connectors and toll selectors, the trunk IT3 is arranged to respond to its seizure to initiate the further extension of the connection to the intercepting operator and to hold the selector and line finder switches in their operated positions. Upon seizure of trunk IT3, the calling line loop is extended through brushes 417 and 418, terminals 421 and 422, and through the back contacts of relay 558 to the windings of line relay 551. The operation of relay 551 causes the successive operation of relays 552, 553 and 554. The operation of relay 553 connects ground through its outer lower front contact over sleeve conductor 569 to sleeve terminal 423 to hold relay 406 of selector LS and to hold the line finder LF and cut-off relay (not shown) of line 401 in the usual manner. The trunk IT3 is shown connected to terminals 731, 732 and 733 in the bank of trunk finder TF and is shown as being in the same group of trunks as are the trunks IT1 and IT2, having the common group relay 701. The operation of relay 553 connects ground through its inner lower front contact, the lower back contact of relay 555 and the uppermost back contact of relay 557 to conductor 700 thereby operating the group relay 701. The operation of relay 554 connects battery through the winding of the cut-off relay 555 in parallel with resistance 559 through the upper front contact of relay 554 and the inner upper back contact of relay 557 to the sleeve conductor 563 connected to terminal 733 in the bank of finder TF. The trunk finder TF, or a similar finder having

access to trunk IT3, is thereupon operated in the manner hereinbefore described to step its brushes up to the level in which the terminals of trunk IT3 are located and to rotate its brushes into engagement with these terminals. When brushes 761, 762 and 763 engage the terminals 731, 732 and 733, the cut-off relay 555 is connected through brush 763, the lower winding of relay 710, lower back contact of relay 708, lower winding of relay 707, to ground at the inner lower front contact of relay 705. The finder switch TF is thus stopped on the terminals in question and extends the connection from trunk IT3 to the outgoing trunk circuit OT. The operation of relay 555 connects the source of ringing current 560 through the lower front contact of relay 555 and through condenser 567 to one of the incoming line conductors thereby transmitting a ringing tone to the calling subscriber. Relay 555 also disconnects the ground at relay 553 from group conductor 700. The operation of relay 555 closes a circuit from battery through the winding of relay 556, through the upper front contact of relay 555, and the lower back contact of relay 557, conductor 562, through terminal 732 and brush 762 conductor 772 of the outgoing trunk circuit OT, lower winding of relay 802, and through resistance 806 to ground at the lower back contact of relay 810. Relay 802 operates but relay 556 is marginal and does not operate in this circuit. The operation of relay 802 causes the further extension of the intercepted call through trunk circuit OT out over trunk 900 to the incoming trunk circuit IT at the intercepting operator's position in the manner hereinbefore described. When relay 810 operates the tripping resistance 820 is connected to conductor 772 as hereinbefore described to cause the operation of relay 556. Relay 556 locks through its inner upper front contact and resistance 564, over sleeve conductor 563, through terminal 733 and brush 763, through the inner lower front contact of relay 710, inner lower back contact of relay 706, outer lower front contact of relay 708, sleeve conductor 773 of trunk-finder TF and over sleeve conductor 819 of the outgoing trunk circuit OT, lowermost front contact of relay 810, to ground at the front contact of relay 809. The operation of relay 556 also causes the operation of relay 557. Relay 557 locks under control of relay 554, and causes the release of the cut-off relay 555 to disconnect the audible ringing tone. With relays 556 and 557 operated, a supervisory circuit is closed from battery through the upper winding of relay 558 of trunk IT3, outer upper front contacts of relays 553 and 556, over conductor 561, through terminal 731 and brush 761 of trunk-finder TF, uppermost back contact of relay 706, uppermost front contact of relay 710, conductor 771, upper back contact of relay 825 of the outgoing trunk circuit OT, windings of relay 812, winding of relay 811, induction coil 816, back contact of relay 808, middle lower front contact of relay 810, lower back contact of relay 825, conductor 772, lowermost front contact of relay 710, lowermost back contact of relay 706, brush 762 and terminal 732 of trunk finder TF, conductor 562, lowermost front contact of relay 557, through the lower winding of relay 558 to ground. Relay 812 operates in this circuit but relay 558 is marginal and does not operate due to the high resistance of the lower winding of relay 812; relay 811 being polarized does not operate because the current is not in the operating direction. Since 75

relay 811 does not operate, relay 814 remains non-operated. The operation of relay 812 causes the operation of relay 813 and holds relay 809 operated. Relay 813 connects the windings of relay 815 to the conductors of trunk 900 causing the operation of relay 901. The lamp 902 is energized, and the audible ringing tone source 907 is connected to the upper conductor of trunk 900 as a result of the operation of relays 904 and 905 as hereinbefore described. When the call is answered by inserting the plug 951 of cord CC2 into jack 903, relays 952, 953 and 906 are operated, relays 954 and 955 are operated, and relays 904 and 905 are released all as hereinbefore described. With relays 904 and 905 released and with relay 955 operated, the windings of induction coil 962, relay 957 and relay 958 are bridged across the conductors of trunk 900, thereby causing the operation of relay 957. Relay 958 does not operate because, due to the non-operation of relay 814 of the outgoing trunk circuit, the current is not in the required direction, and relay 815 of the outgoing trunk circuit does not operate because the current is not strong enough to operate this marginal relay. The operation of relay 957 prevents the operation of relay 959. Since relay 815 does not operate, the lower high resistance winding of supervisory relay 812 is not short circuited so that relay 558 of the trunk IT3 is not operated and the current supplied through the windings of relay 551 over the calling loop is not reversed as a result of the answering of the call.

The voice currents between the calling station and intercepting operator are transmitted through condensers 565 and 566 of trunk circuit IT3 and through condensers 821 and 822 of the outgoing trunk circuit OT. The call may be from a local operator instead of from a calling subscriber's station in which case it may be found desirable to flash the local operator by operating the flashing key 961 at the intercepting operator's position. If the flashing key 961 is operated, the windings of relays 957 and 958 are intermittently eliminated from the cord bridge causing the alternate operation and release of relay 815 of the outgoing trunk circuit OT. The alternate operation and release of relay 815 causes the intermittent short circuiting of the lower winding of relay 812, resulting in the alternate operation and release of marginal relay 558 of trunk IT3. The operation and release of relay 558 in response to the operation of the flashing key causes the temporary reversal of the connections between the windings of relay 551 and the calling loop.

When the calling subscriber replaces the receiver on the receiver hook relay 551 releases. Relays 552, 553 and 554 release in turn. The release of relay 553 opens the supervisory circuit between trunk circuit IT3 and outgoing trunk circuit OT causing the release of relay 812. The release of relay 812 causes the release of relay 809; and the release of relay 809 causes the release of relays 810, 710 and 556. The release of relay 710 causes the trunk-finder TF to be restored to normal as hereinbefore described. The release of relay 556 causes the release of relay 557 and disconnects ground from conductor 569 causing the release of the selector LS and line finder LF and the return of these switches to normal in the usual manner. The aforementioned release of relay 812 causes the successive release of relays 813 and 815 of the outgoing trunk circuit OT and the release of relay 957 of

the cord circuit CC2. The release of relay 957 closes a circuit, for operating relay 959, from battery through the winding of relay 959, back contact of relay 957, outer back contact of relay 956, upper back contact of key 961 to ground at the upper front contact of relay 955. The operation of relay 959 closes a circuit for lighting the cord lamp 964 as a disconnect signal and causes the release of relay 953 and the operation of relay 963 by connecting the winding of relay 963 in series with relay 906 of the incoming trunk circuit IT in place of the winding of relay 953. Relay 906 releases due to the high resistance of the winding of relay 963. Relay 962 closes a holding circuit for relay 959. The release of relay 953 causes the successive release of relays 954 and 955. The release of relay 906 of trunk circuit IT restores the bridge across trunk 900 awaiting another call. When the intercepting operator removes the plug 951 from the answering jack 903, the resultant release of relays 953 and 959 completes the return to normal of all circuit units involved in the connection.

If the called line number is an unassigned number in a partially assigned group of one-hundred numbers, the corresponding terminals in the bank of the connector switches are connected to an intercepting trunk. The terminals 521, 522 and 523 represent such a called number and are shown connected to the intercepting trunk circuit IT4 which is similar in all respects to the trunk IT1. The trunk IT4 is connected to terminals 741, 742 and 743 in the bank of trunk finder TF and to corresponding sets of terminals in the banks of other trunk finders similar to TF. The operation of the trunk circuit IT4 is similar to that hereinbefore described for trunk IT1 and the extension of a connection from intercepting trunk IT4 to the outgoing trunk circuit OT is completed in the same manner as that hereinbefore described for a connection from trunk IT1 except that the relay 802 responds to either alternating current, through its lower winding and condenser 804, incoming from the source of ringing current at connector LC or to direct current through its lower winding during the silent period of the ringing cycle. The operation of relays 807, 808, 809 and 810 and the release of relays 802, 807 and 808 occurs in the manner hereinbefore described. The temporary connection of resistance 820 to conductor 772 causes the operation of tripping relay 506 of the connector LC, a supervisory circuit being thereupon closed from battery through the upper winding of relay 504, uppermost front contacts of relay 506 and 511, brush 517 and terminal 521, conductor 461 of trunk IT4, terminal 741 and brush 761 of trunk-finder TF, uppermost back contact of relay 706, uppermost front contact of relay 710, conductor 771, upper back contact of relay 825, windings of relays 812 and 811, induction coil 816, back contact of relay 808, middle lower front contact of relay 810, lower back contact of relay 825, conductor 772, lowermost front contact of relay 710, lowermost back contact of relay 706, brush 762 and terminal 742, conductor 462, terminal 522 and brush 518, lowermost front contacts of relays 511 and 506, through the lower winding of relay 504 to ground. Relay 504 being marginal does not operate on account of the high resistance of the lower winding of relay 812. Relay 812 operates but relay 811 does not operate, the current through its winding being in the non-operating direction. Relay 812 holds relay 809 operated and closes a circuit for operating relay 813. The connection is fur-

ther extended over trunk 900 to the incoming trunk circuit IT, the lamp 902 is energized, and the call is answered all in the manner hereinbefore described for a call incoming from intercepting trunk IT3. Since relay 815 of the outgoing trunk OT is not operated upon answer of the intercepting operator, the lower winding of relay 812 is not short circuited and relay 504 of the connector LC is not operated. Upon release of the connection by the calling subscriber or operator, the release of relay 501 of the connector LC causes the release of relay 502. Since relay 504 was not operated, relays 511 and 506 release and the connector LC is immediately restored to normal in the usual manner, as are also the selector LS and line finder LF. The release of relay 511 causes the release of the cut-off relay 451 of trunk IT4 and opens the supervisory circuit through the windings of relays 504 and 812. The release of relay 812 causes the outgoing trunk circuit OT, trunk finder TF, and incoming trunk circuit IT to be restored to normal as hereinbefore described. A disconnect signal is given to the intercepting operator in the manner hereinbefore described and when the plug 951 is removed from jack 903 all of the circuit units involved in the connection are again normal.

If the called line is one which is temporarily removed from service, it is connected to a plugging-up line circuit, the cut-off relay of the line being blocked operated to disconnect the line relay from the line terminals in the connector banks. Such a line is represented by the line 601 serving the subscriber's station C in Fig. 6. The plugging-up line PL comprises a plug 602, the plug 603 and the cord connecting these plugs. With the plug 602 inserted in place of the heat coils at the main distributing frame MDF and the plug 603 inserted in an available jack in one of the jack panels associated with the main frame, the conductors of line 601 are extended over the upper pair of conductors of plug 603 and jack 604 to a line 605 leading to the local test board 606; and the conductors from the connector switch terminals normally connected to the line 601 are extended over the lower pair of conductors of plug 603 and jack 604 and over conductors 607 and 608 to the intercepting trunk circuit IT5. The line conductors 607 and 608 are further extended and together with the sleeve conductor 609 connect to terminals 751, 752 and 753 in the bank of trunk finder TF.

Assuming the station A in Fig. 4 to have called the number of line 601, seizure of terminals 531, 532 and 533 by the connector LC in response to the dialing of the last digit, extends a connection to trunk circuit IT5. In the trunk circuit IT5, the condenser 610 and upper winding of relay 611 are bridged across conductors 607 and 608, so that closure of the ringing circuit by the operation of relay 511 of connector LC causes the operation of relay 611. The impedance of condenser 610 and relay 611 is high enough to prevent the operation of tripping relay 506 of the connector. The operation of relay 611 in response to the ringing current from connector LC causes the operation of relay 613. With relay 613 operated, the lower winding of relay 612 is connected in parallel with the upper winding of relay 611 so that relay 612 is also operated by ringing current from connector LC. Relays 611 and 612 are held operated, independently of the ringing current, by a circuit from battery through the lower winding and inner front contact of relay 611 and the outer upper front contact of relay 613, in

parallel with battery through the upper winding of relay 612, thence through the inner upper back contact of relay 614, to ground through the upper front contact of relay 612. With relay 612 operated, ground is connected from the lower back contact of relay 614, through the lower front contact of relay 612 to the group conductor 700 (or a similar conductor if the trunk IT5 is in a different subgroup from that which includes the trunk IT1). The operation of the associated group relay such as relay 701 initiates the operation of an idle trunk finder such as TF to establish connection with terminals 751, 752 and 753 or the corresponding set of terminals in finders other than TF. Assume the finder TF to be the one thus started in search for the calling trunk. When the brushes of finder TF reach the terminals to which the trunk IT5 connects, a circuit is closed from battery through the cut-off relay 614 of the trunk circuit IT5, lower front contact of relay 613, over sleeve conductor 609 and through terminal 753 to brush 763 of trunk finder TF, and thence to ground through the windings of relays 710 and 707 as hereinbefore described. Relay 614 operates and the trunk finder extends the connection from trunk IT5 through its brushes over conductors 771 and 772 to the outgoing trunk circuit OT in the manner hereinbefore described. Relay 614 locks over conductor 609, through terminal 753 and brush 763 to the ground at relay 809 of the outgoing trunk circuit. Relay 614 disconnects the ringing circuit bridge from conductors 607 and 608, and opens the locking circuit for relays 611 and 612, causing the release of these relays. The release of relay 611 causes the release of relay 613.

Ringing current from the connector LC is now transmitted over conductor 608, through terminal 752 and brush 762, the lowermost back contact of relay 706 and lowermost front contact of relay 710, over conductor 772, through the lower winding of relay 802, and through resistance 806 or condenser 804, to ground at one of the lower back contacts of relay 801. Relay 802 is thus operated to initiate the operations hereinbefore described for lighting the signal lamp 902 at the intercepting operator's position. The further operation of trunk circuits OT and IT, in response to the answer of the operator, is the same as that hereinbefore described.

When the connection is released by the calling subscriber, the connector, selector, and line finder switches are immediately released in the usual manner and a disconnect signal is given to the intercepting operator. The trunk finder TF, the outgoing trunk circuit OT, the incoming trunk circuit IT, and the cord circuit CC2 are restored to normal in the manner hereinbefore described on a call incoming from trunk IT4.

Should the plugging-up line PL be connected to the terminals of a line which normally receives ringing current over the tip conductor instead of over the ring conductor, the connections at the intermediate distributing frame IDF being such as to secure this result, then the ringing current incoming to the outgoing trunk circuit OT on a call intercepted from this plugging-up line will energize relay 801 instead of relay 802. The energization of the upper winding of relay 801 either by ringing current through its upper winding and condenser 803 or by direct current (during the silent period of the ringing cycle) through this winding and resistance 805 is effective to operate this relay. Relay 801 connects ground to sleeve conductor 819 and causes the success-

sive operation of relays 825 and 826. Relay 825 reverses the conductors incoming to the trunk circuit OT with respect to the windings of relays 812 and 811 so that the subsequent operation of relay 810 will be effective to complete the connection from the conductor over which ringing current is being received to the low tripping resistance 820. Relay 826 also closes a locking circuit for relay 801, from battery through its lower winding, lowermost front contact of relay 826, upper back contact of relay 810, upper front contact of relay 826, to ground at the inner lower front contact of relay 801. The connection from ground at the inner lower front contact of relay 801 through the upper front contact of relay 826 also causes the operation of relay 807. The further operation of the outgoing trunk circuit OT and the operation of the incoming trunk circuit IT is similar to that hereinbefore described. After relay 810 operates, relay 801 releases but relay 825 is held operated by a circuit from battery through its lower winding, inner lower front contact of relay 826, over sleeve conductor 819, through the lowermost front contact of relay 810, to ground at the front contact of relay 809. Release of the connection is completed in the manner hereinbefore described, relays 825 and 826 being released when relay 809 releases.

What is claimed is:

30. 1. In a telephone system, selector and connector switches for establishing connections between calling and called lines, a trunk finder switch, a first intercepting trunk connected to terminals in the bank of said selector and to terminals in the bank of said trunk finder, a second intercepting trunk connected to terminals in the bank of said connector and to terminals in the bank of said trunk finder, means associated with each of said trunk circuits and responsive to their seizure for initiating operation of said trunk finder to connect with either of said trunks, an operator's position, a third trunk individual to said trunk finder and terminating at said operator's position, a signal for said third trunk at said position, means for closing a direct current signaling circuit over said first intercepting trunk and said third trunk, means for closing an alternating current signaling circuit over said second intercepting trunk and said third trunk, and means responsive to signalling current received from either of said intercepting trunks for causing the operation of said signal.
2. In a telephone system, lines, local selector switches for use in establishing connections between calling and called lines, toll selectors for use in extending incoming toll calls to said lines, connector switches for selecting and connecting to any one of said lines, terminals in the banks of said local selector switches which represent unequipped lines, terminals in the banks of said toll selector switches which represent unequipped lines, terminals in the banks of said connector switches which represent unequipped lines, trunk finder switches, trunks from said terminals which represent unequipped lines terminating in the banks of said trunk finder switches, means responsive to the seizure of one of said trunks by one of said selector or connector switches for initiating the operation of an idle trunk finder to connect with the seized trunk, intercepting operators' positions, and other trunks one for each of said trunk finders for extending an intercepted call to one of said positions.
75. 3. In a telephone system, lines, local selector

switches for use in establishing connections between calling and called lines, toll selectors for use in extending incoming toll calls to said lines, connector switches for selecting and connecting to any one of said lines, terminals in the banks of said local selector switches which represent unequipped lines, terminals in the banks of said toll selector switches which represent unequipped lines, terminals in the banks of said connector switches which represent unequipped lines, plugging-up lines for use in intercepting calls to and from subscribers' lines which are temporarily removed from service, trunk finder switches, trunks from said terminals which represent unequipped lines and trunks from each of said plugging-up lines, all of said trunks terminating in the banks of said trunk finder switches, means responsive to the seizure of one of said trunks by one of said selector or connector switches for initiating the operation of an idle trunk finder to connect with the seized trunk, intercepting operators' positions, and other trunks one for each of said trunk finders for extending an intercepted call to one of said positions.

4. In a telephone system, lines, automatic switches for use in establishing connection between calling and called lines, intercepting trunks connected to terminals in the banks of said switches, trunk finders, said trunks terminating in the banks of said trunk finders, means in certain of said trunks effective in response to their seizure to initiate the operation of an idle one of said trunk finders to connect with a seized trunk, and means in others of said trunks effective in response to ringing current received from the automatic switches by which they are seized to initiate the operation of an idle one of said trunk finders to connect with a seized trunk.

5. In a telephone system, lines, automatic switches for use in establishing connections between calling and called lines, intercepting trunks connected to terminals in the banks of said switches, trunk finders, said trunks terminating in the banks of said trunk finders, means in each of said trunks for initiating the operation of an idle trunk finder to connect with a seized trunk, intercepting operators' positions, other trunks one from each of said trunk finders to said positions, signals one for each of said other trunks, and means associated with each of said other trunks responsive to direct or alternating current received over said intercepting trunks for causing the operation of the corresponding signal.

6. In a telephone system, lines, automatic switches for use in establishing connections between calling and called lines, intercepting trunks connected to terminals in the banks of said switches, trunk finders, said trunks terminating in the banks of said trunk finders, means in each of said trunks for initiating the operation of an idle trunk finder to connect with a seized trunk, intercepting operators' positions, other trunks one from each of said trunk finders to said positions, means associated with each of said other trunks for receiving signalling current over either one of the line conductors of said intercepting trunk, and means in each of said other trunks and effective in case said signalling current is received over one of said line conductors for reversing the conductors from the trunk finder.

7. In an automatic telephone system, lines, intercepting operators' positions, trunks from automatic offices to said positions, a signal for each of said trunks, trunk finders in said automatic offices there being one of said trunk finders for each

of said trunks, automatic switches in said automatic offices for use in establishing connections between calling and called lines, terminals in the banks of said switches which represent unequipped lines, intercepting trunks connected to said terminals and leading to terminals in the banks of said trunk finders, means responsive to the seizure of one of said intercepting trunks for initiating the operation of one of said trunk finders to connect with the seized trunk, and means in the trunk associated with said trunk finder responsive to alternating or direct current received over said intercepting trunks for causing the operation of the corresponding one of said signals.

8. In an automatic telephone system, lines, and intercepting operator's position, a trunk from an automatic office to said position, a signal for said trunk at said position, a finder switch in said automatic office individual to said trunk, switches in said automatic office for use in establishing

connections between calling and called lines, terminals in the banks of said switches which represent unequipped lines, intercepting trunks connected to said terminals and leading to other terminals in the bank of said finder switch, means responsive to the seizure of one of said intercepting trunks for causing said finder switch to connect with said seized intercepting trunk, means for receiving ringing current over either of the line conductors of said finders switch, means effective if ringing current is received over one of said conductors for reversing said conductors from said finder switch, means responsive to the receipt of said ringing current for causing the operation of said signal, a link circuit at said operator's position arranged for connection with said trunk to answer said signal, and means rendered effective in consequence of the answer of said operator for closing a connection to trip said ringing current.
